UNITED STATES PATENT OFFICE.

OSCI J. BAINUM, OF PAXTON, ILLINOIS.

INDIVIDUAL-DRINKING-CUP HOLDER.

1,032,527.

Specification of Letters Patent. Patented July 16, 1912.

Application filed August 30, 1911. Serial No. 646,859.

To all whom it may concern:

Be it known that I, Osci J. Bainum, a citizen of the United States, residing at Paxton, county of Ford, and State of Illinois, have invented certain new and useful Improvements in Individual-Drinking-Cup Holders, of which the following is a specification.

This invention relates to individual drinking cup holders.

In factories, schools, and other places where a number of persons have to use drinking cups, it is desirable, from sanitary reasons, for each individual to have his own drinking cup or vessel. Some States, notably the State of Illinois, at the present time require individual drinking cups in public places, such as factories, schools, etc.

The present invention is designed to afford a new holder for drinking cups, particularly collapsible drinking cups with which it is specially designed for use and my object is to provide a simple, inexpensive, light, durable, and strong holder having a base or body of new form adapted especially for connection to the side of a school desk, but which may be used in other places, combined with spring-actuated holding arms or members arranged in a new manner and particularly adapted to embrace the side of a drinking cup of the collapsible type for the purpose of holding it, ready for instant and ready removal.

I wish it understood that the invention is susceptible of modifications and I lay claim to all changes coming within the spirit and scope of the invention.

Preferred forms of the invention are set forth fully hereinafter and shown in the accompanying drawings in which:—

Figure 1 is a perspective view of a part of a school desk and seat showing the position in which the holder and cup may be conveniently placed; Fig. 2, a perspective of the holder; Fig. 3, a perspective of a collapsible cup which is specially adapted for use in connection with my invention; Figs. 4 and 5 details of another form of holder, and Fig. 6, a detail of the cup of Fig. 3 when opened ready for use.

The top of an ordinary school desk is shown at 1 and the back of the preceding seat at 2.

My invention (Figs. 1 and 2) has a preferably wooden base 3 and a wooden back 4, although the latter might be omitted, but

it is preferably employed so that if the cup or drinking vessel is wet, it will not come against the side of the desk, but will abut the back 4. The base 3 and back 4 are connected together in any preferred manner. The base 3 is provided with one or more screw holes 5 through which any suitable fastening may be passed and engaged with the seat back 2.

Secured by any suitable fastening 6 passing therethrough into the base 3, is a double spring arm, preferably made from a single piece of flat springy metal, of general circular shape, having the arms 7 and 8 provided with out-turned rounded ends 9 to facilitate the sidewise introduction of the drinking cup between them. Secured to the base at 10 is a retaining spring arm or a support 11 provided with a rounded outwardly turned end 12 which is so positioned that it will come approximately at the center of the end of the drinking cup.

The drinking cup which is specially adapted for use in connection with my invention is of the type shown in closed condition in Fig. 3 and in open position in Fig. 6, this cup 13 being of metal and composed of collapsible or telescopic sections.

When the cup 13 is collapsed, it can be slid in between the end 9 of the arms 7 and 8 in a sidewise direction as indicated by the arrow in Fig. 1, and, similarly, it can be removed by pulling it from between the arms 7 and 8. On account of its general cylindrical construction, the arms 7 and 8 are adapted to grasp the cup 13 when it is in the holder, as shown in Fig. 1, firmly retaining it, but without interfering with its ready removal at any time. The retaining arm 11 bears against the central part of the cup 13 when the latter is in the holder, and prevents the cup from coming out from between the arms 7 and 8 and the resiliency of this arm permits the cup to be readily slid into or removed from the holder.

With my invention, each pupil has his or her own drinking cup suitably held in an inconspicuous yet convenient position at the side of the desk and the common drinking from a general cup or glass is obviated.

In the modification shown in Figs. 4 and 5, the base 3^a and back 4^a are made from a single piece of sheet metal, preferably a steel stamping and the base has an integral, but not necessarily resilient, retaining arm 11^a. The double spring arm 7^a is seated in

a recessed part 8^a of the base and secured by a rivet 6^a:

In both forms, the parts 11, 11^a may be dispensed with as the double spring 7, 7^a will hold the cup, but are preferably used to prevent a child from pulling the cup outwardly and leaving it projecting into the aisle.

The back and base of the form shown in Figs. 4 and 5 may be suitably japan-enamelled.

Having thus described my invention, what I claim as new and desire to secure by Letters Patent, is:

- 15 1. In an individual drinking cup holder, the combination with a base, and a back connected together, of a pair of spring actuated arms carried by said parts and adapted to embrace the drinking cup, and
- 20 2. a spring actuated retaining arm carried by said parts adapted to bear against the end of a drinking cup when the latter is held between the arms aforesaid and which holds the cup against the back aforesaid.
- 25 3. The herein-described individual drinking cup holder embodying a base and back con-

nected together and arranged substantially at right angles to each other, a one-piece resilient member of general circular form having free springy parts adapted to embrace a drinking cup when placed between them and connected intermediate said springy parts to the aforesaid base; and a springy retaining arm secured to the base and having a free part positioned so that it will bear on the end of a drinking cup held by the arms aforesaid.

3. In an individual drinking cup holder, the combination with a flat base and flat back connected together and disposed substantially at right angles to each other, of spring actuated arms secured to one of said parts which are disposed substantially at right angles to one of said parts and substantially parallel to the other of said parts, and adapted to grasp the sides of the cup.

In testimony whereof, I hereunto affix my signature in presence of two witnesses.

OSCI J. BAINUM.
